UNITED STATES PATENT OFFICE.

LEWIS S. CHICHESTER, OF NEW YORK, N. Y., ASSIGNOR TO JOHN J. TYLER,
OF SAME PLACE.

IMPROVEMENT IN MACHINES FOR HULLING AND SCOURING GRAIN.

Specification forming part of Letters Patent No. 159,080, dated January 26, 1875; application filed December 12, 1874.

To all whom it may concern:

Be it known that I, LEWIS S. CHICHESTER, of the city and State of New York, have invented and made an Improvement in Hulling and Scouring Machines, of which the following is a specification:

This invention is for the purpose of removing the hulls from wheat and other grain previous to its being ground or otherwise prepared for market; and consists in peculiarly-constructed rubbing-hands, that revolve in a suitable case, in combination with deflectors, and a trunk for a suction-blast to carry away the dust and hulls.

In the drawing, Figure 1 is a vertical section of the hulling apparatus. Fig. 2 shows the rubbing-hands separately in larger size; and Fig. 3 is a section at the line *x x*, representing these rubbing-hands and illustrating their action on the grain.

The rubbing-hands *a a* are composed of three or more V-shaped curved bars. I have shown four extending out from a hub, and each V-shaped bar is corrugated or roughened upon its outer and operative surface, and it is generally concave, the end of the curved bar being in advance of the concave portion, the object being to lessen the centrifugal action of the hands in consequence of the concave surface tending to throw the grain toward the center. Several of the hubs with the hands *a*, according to the size of the huller, are placed side by side on each of the shafts *d* and *e*, and firmly secured by keys or otherwise to those shafts, respectively. These shafts are in boxes upon a frame, *f*, and they are revolved by competent power in the direction of the arrows, and the shafts *d* and *e* are preferably revolved faster than the shaft *c*. Below the hands *a a* there is a concave bottom, *g*, preferably made of wire cloth or similar material, in concave sections, as shown, and these concave bottoms are secured to a frame, *g'*, that is hinged at 7 to the frame *f*, so that it can be swung down to allow for cleaning the grating. There is a cover, *h*, over the rubbers or hands,

with curved adjustable deflectors *k*, each of which is hinged at 2, and raised or lowered by the rod 3, made with holes for a sustaining pin.

The grain is introduced through the hopper *l*, and the quantity is regulated by the damper *4*. The grain accumulates upon each of the curved bottoms *g*, and the rubbers or hands pass through the grain, and the surfaces being inclined toward each other the grains are compressed and rubbed one against the other as the hands pass through the mass, and a portion is, from time to time, thrown, by the centrifugal force, into the next section, to be again operated upon by the hands or rubbers, and so on. The dust and particles of hulls are drawn off by a suction applied to the trunk *k'*.

I remark that it is generally preferable to moisten the grain with water before hulling, because the hulls will be softened and more easily rubbed off, and the grain will be less liable to be broken. The grain is eventually delivered by the spout *6*, and the hulls and dust are drawn up into the trunk *k'* and conveyed away. A separate winnower may be employed, if necessary; and I remark that the period of time in which the grain remains in the apparatus under treatment will depend upon the position of the deflectors *k* and the speed of rotation of the hands or rubbers.

I claim as my invention—

1. The revolving hands or rubbers *a a*, in combination with the adjustable deflectors *k* and trunk *k'*, substantially as set forth.
2. The hands or rubbers made sectionally of a V shape, and curved forward at their ends, and revolved in pairs within the grain-receptacle to loosen and separate the hulls by the rubbing motion specified.

Signed by me this 7th day of December, 1874.

LEWIS S. CHICHESTER.
